UNITED STATES PATENT OFFICE.

BARRY IVOR, OF CHICAGO, ILLINOIS.

DESIGN FOR A LUBRICATOR-PUMP BODY.

SPECIFICATION forming part of Design No. 33,748, dated December 18, 1900.

Application filed November 23, 1900. Serial No. 37,548. Term of patent 7 years.

To all whom it may concern:

Be it known that I, BARRY IVOR, a citizen of the United States, residing at Chicago, in the county of Cook and State of Illinois, have 5 invented and produced a new and original Design for Lubricator-Pump Bodies, of which the following is a specification, reference being had to the accompanying drawings, forming part thereof.

10 Figure 1 is a perspective view of a pump-body, showing my new design; and Fig. 2 is a similar view of the opposite side thereof.

15 As shown in the drawings, the leading or material feature of my design consists of a rectangular-shaped body A, mounted on a semicircular and horizontal portion B, which is supported by a cylindrical part C, resting on a flat circular piece D. One side of the portion B is provided with rectangular openings b and the other side with similar openings b', while one end of said portion is provided with a circular opening b², located about the central part of said end. One side 20 of the portion A of the body is formed with circular openings a, while the opposite side 25

is provided with similar-shaped openings a' in the lower portion of said part. On the surface of the portion A which has the openings a' are projections a², united by a tubular piece a³. At each of the corners of the 30 portion A are located rods or posts E, which have on their upper ends caps e, pointed at their upper ends. The top of the portion A is formed with a number of openings a⁴ near two of its sides, and with enlargements a⁵, and 35 also with a larger opening a⁶, which is located between two of said enlargements.

Having described my invention, what I claim as new, and desire to secure by Letters Patent, is—

40 The design for a lubricator-pump body, substantially as herein shown and described.

In testimony whereof I have signed my name to this specification in the presence of two subscribing witnesses.

BARRY IVOR.
